G. A. LYON

BRACE BAR BUFFER

Filed Jan. 20, 1922

Patented Sept. 11, 1923.

1,467,385

UNITED STATES PATENT OFFICE.

GEORGE ALBERT LYON, OF PHILADELPHIA, PENNSYLVANIA.

BRACE-BAR BUFFER.

Application filed January 20, 1922. Serial No. 530,547.

To all whom it may concern:

Be it known that I, GEORGE ALBERT LYON, a citizen of the United States, and resident of Philadelphia, county of Philadelphia, 5 State of Pennsylvania, have made a certain new and useful invention relating to Brace-Bar Buffers, of which the following is a specification, taken in connection with the accompanying drawing. This application is 10 a partial division of my applications Serial Nos. 351,284, filed January 14, 1920, and 358,239, filed February 12, 1920. That is, this case contains subject matter taken therefrom.

15 This invention relates especially to automobile buffers with which may be combined brace bars, supporting members, or auxiliary buffer portions which may be secured or connected to the automobile or other vehicle 20 frame members to reenforce and strengthen them. For this purpose special frame ends which may be riveted or otherwise connected to the forward ends or portions of the usual channel section frame members of the vehicle 25 may advantageously be provided with laterally extending supporting bosses on one or both sides of each frame member and an enclosing supporting clamp may cooperate with each boss which, if desired, may be 30 recessed to receive and align the brace bar portion. The supporting boss may, if desired, have retainer lugs or portions and aligning faces to engage and align the supporting clamp which may enclose the boss and cooperating 35 brace bar or other supporting portions of the buffer so that the brace bar portions may thus be securely clamped or connected to each of the frame members so as to have a desirable reenforcing action thereon and 40 at the same time support the buffer front of any suitable construction which may be in the same plane or bent upwards in some cases so as to be arranged in a higher plane than the connected rear supporting portions. The 45 brace bar or supporting portions may, if desired, have integrally or otherwise connected end loops and adjacent turned connector portions to which may be detachably or otherwise connected the buffer front portions 50 preferably formed of spring strip or other resilient elements, so that these impact receiving members may have the desired resilient action under collision conditions. It is sometimes desirable to form the brace bar 55 or supporting portion of the buffer of one or more pieces of resilient spring steel strip

which may have looped end portions extending out into protective position in front of the vehicle wheels so as to form the end loops for the buffer while the cooperating 60 spring strip reenforcing members and end and center clamping devices which may be used to connect and stiffen the strips give additional strength and reliability to this construction.

65 In the accompanying drawing showing in a somewhat diagrammatic way various illustrative embodiments of this invention.

70 Fig. 1 is a plan view partly in section showing one form of construction.

75 Fig. 2 is an enlarged side sectional view taken approximately along the line 2—2 of Fig. 1.

Fig. 3, 4 and 5 are plan views showing other illustrative forms of buffer, and

75 Fig. 6 is an enlarged transverse section showing the attachment of the Fig. 5 buffer.

80 In the illustrative embodiment of the invention shown in Fig. 1, the brace bar or supporting portion of the buffer may comprise one or more connected strips of spring steel or other suitable and preferably resilient material having end loop portions. As illustrated the brace bar portion or strip 7 may extend beyond the special frame ends or 85 supporting bosses 15 and be provided with stiffening connector portions 8, 9 and 10, 11 which may extend behind and around the one or more spring strips having cooperating connector portions 5, 6 which may have 90 the integral end loops 3 and curved resilient portions 4 as well as the front connector portions 2, if desired. In this case the buffer front or impact receiving portions may comprise the spring strips 1 cooperating with 95 the front connector portions and if desired having more or less aligning action thereon, these parts being connected by the enclosing clamping devices or clips 12, which may be tightened around the parts by the 100 bolts or nuts 13.

105 The supporting or brace bar portions of the buffer may as indicated in Fig. 2 be clamped or connected to supporting bosses 15 which may extend on one or both sides of the special frame ends rigidly connected to the usual channeled frame members or 110 goose necks 22. Any convenient means for connecting these parts may be used and as indicated the supporting boss which may project on both sides of the frame member may be formed with an integral supporting

or securing portion 23 extending within the channeled frame member and welded, riveted or otherwise connected thereto in a rigid way. This supporting boss may of course accommodate the end of the usual spring 23' which may be secured by a spring hanger bolt 14 passing through the boss if desired. This supporting boss may be formed with a recess 18 of such size as to accommodate the one or more spring strips constituting this supporting brace bar portion of the buffer and a straight or rectangular sectioned recess of this character may support the flat sectioned strips as indicated in Fig. 2 in connection with a supporting clamp, such as 16, which may be arranged around these parts and strongly clamped upon the same as by a tightening bolt 19 passing through the ends 24 of this clamp. It is usually advantageous to form the one or more bosses provided on each frame member with a retainer lug or portion such as 21 projecting outward to at least a slight extent beyond the cooperating face 20 of the boss which may be substantially flat or vertical, if desired. The supporting clamp of wrought or malleable material may be sufficiently expanded to be slipped over this retainer portion and then tightened inside the same which definitely holds the parts in this securing position and positively prevents the clamps slipping sidewise from the supporting boss. As indicated in Fig. 1 two such supporting clamps 16, 17 may be used on each supporting boss or frame end 15 and in this way an amply strong and rigid connection may be secured between the supporting or brace bar portion of the buffer and the frame ends so as to considerably strengthen and reenforce them against lateral yielding and breakage.

Fig. 3 shows another form of construction in which the supporting or brace bar portion 65 may be a single strip of spring steel or other resilient material having the outwardly extending connector portions 62 and the curved portions 63, 64 which give greater resilient yield to the parts. The buffer front may in this instance comprise one or more strips having end loops 58, 59 and inturned connector portions or ends 60, 61 to be clamped or connected to the cooperating connector portion 62 as by the enclosing clips 70, 71. When as illustrated the impact receiving or front portion of the buffer comprises two overlapping strips 56, 57 a considerable degree of lateral adjustment is thus secured and these front strips may be clamped in any desired adjusted position by the enclosing clamps 12. The supporting portion 65 of this type of buffer may be similarly clamped or connected to the automobile frame members in the manner previously described, or if desired, other supporting devices may be used on this or other

illustrated types of construction, and for this purpose separate attaching members, such as 67, which may be clamped or connected to the automobile frame members, may be formed with bent connector portions 66, so that they can be connected as by the clamping devices or clips 72, 73 to this supporting or transverse portion 65 of the buffer. It is thus unnecessary to directly connect this or the other types of buffer to special supporting bosses such as illustrated in Fig. 2.

As shown in Fig. 4 the entire device may in some cases be formed of a single strip of resilient material which may have a brace bar portion 30 formed, if desired, with a forwardly projecting or convex section portion 31 which may die out at about the point 32 on each side so as to give the desired degree of resilient yield to the forwardly and outwardly curving portions 33, 37 and the connected end loops 34, 38. The integral connected impact receiving portions 35, 39 may be of such length that their ends 36, 40 overlap to a considerable extent to give a reinforced buffer front when these ends are connected in any suitable way as by enclosing clips or clamps 24. Fig. 5 shows still another arrangement in which the brace bar portion 41 of spring strip material may, if desired, be similarly stiffened by being cupped or bent in cross-section throughout at least the brace bar portion which may be connected to the frame or other members of the automobile, and if desired this bent portion may die out at about the points 42 so as to render more resilient the curved yielding portions 43, 47 and the end loops 44, 48. The connected front or impact receiving portions 45, 49 which are thus spaced amply away from the brace bar portion 41 may be connected together in any suitable way preferably in connection with one or more reinforcing front members of any suitable character, such as the resilient front strip 51 so as to form a reinforced or multiple thickness strengthened buffer front which gives increased resistance and efficiency in absorbing collision impacts. If desired, suitable clamping devices, such as 12, may connect these front portions and may enclose the front strips adjacent the ends of the reinforcing strip. It is also desirable in some cases to have an additional center clamp such as 54 which may enclose the ends 36, 50 of the front strips when they are substantially in line and hold them securely and rigidly against the cooperating portion of the reinforcing front strip.

These types of combined brace bar and buffer may also in many cases be advantageously used as rear buffers by directly connecting the brace bar portions to the rear springs of an automobile. As indicated in Figs. 5 and 6 the cupped or curved section

brace bar portion 41 may fit against the elliptical or other rear springs 55 of the automobile so as to engage the same at the contact edges 56. The parts may be securely 5 clamped in this position by devices comprising the clamping plates 52 and cooperating clamping U-bolts 53 which may have the yoke portion extending around the spring while the shanks of these U-bolts are preferably 10 forced against the contact edges of the brace bar portion of the buffer. For this purpose the clamping plate may be formed with angularly arranged aligning ends 37 so that when the nuts 54 are tightened on these U-bolts or other connectors the aligning ends 15 throw the shanks of these bolts toward each other so as to forcibly engage the contact edges 38 of the brace bar portion although considerable back lash or angular space may 20 be provided in each of the bolt holes. It is of course understood that with such a type of clamping device the buffer may be loosely connected to the rear springs and then slipped up or down along the same so as to 25 bring it into the desired angular position before finally tightening or clamping the bolts to prevent further movement.

This invention has been described in connection with a number of embodiments, 30 forms, proportions, parts, arrangements, materials, methods of connection and use, to the details of which disclosure the invention is not of course to be limited since what is 35 claimed as new and what is desired to be secured by Letters Patent is set forth in the appended claims:

1. The automobile buffer formed of resilient spring strip and having a rear transverse member, spring strip attaching members 40 adapted to be connected to the automobile and having bent connector portions to be adjustably clamped to the cooperating connector portions of said rear transverse member, and having a buffer front member spaced considerably ahead of the connector portions of said rear member, said rear member having integral looped ends extending 45 out into protective position adjacent the automobile wheels and having inturned connector portions, front reenforcing strips having their ends clamped to said inturned connector portions and a central clamping device enclosing the front member adjacent its central portion to stiffen and strengthen 50 the same.

2. The automobile buffer formed of resilient spring strip and having a rear transverse member, attaching members adapted 60 to be connected to the automobile and having connector portions to be adjustably clamped to the cooperating connector portions of said rear transverse member, and having a buffer front member spaced considerably ahead of the connector portions of said rear member, said rear member having 65

integral looped ends extending out into protective position adjacent the automobile wheels and having inturned portions, front reenforcing strips having their ends clamped to said inturned portions and a central 70 clamping device enclosing the front member adjacent its central portion to stiffen and strengthen the same.

3. The automobile buffer formed of resilient strip and having a rear transverse member, attaching members adapted to be connected to the automobile and having connector portions to be adjustably secured to the connector portions of said rear transverse member, and having a buffer front member spaced considerably ahead of the connector portions of said rear member, said rear member having integral looped end portions extending out into protective position adjacent the automobile wheels and having inturned connector portions and a front reenforcing member secured to the other buffer elements by enclosing clamping devices including a substantially central clamping device. 75

4. The automobile buffer formed of resilient strip and having a rear transverse member, attaching members adapted to be connected to the automobile and having connector portions to be secured to the connector portions of said rear transverse member, and having a buffer front member spaced considerably ahead of the connector portions of said rear member, said rear member having looped end portions extending 90 out into protective position adjacent the automobile wheels and a front reenforcing member secured to the other buffer elements by enclosing clamping devices. 95

5. The automobile buffer formed of resilient spring strip and having a rear transverse member, and having a buffer front member spaced considerably ahead of the lateral portions of said rear member, said rear member having integral looped ends 100 extending out into protective position adjacent the automobile wheels and having inturned portions, front reenforcing strips having their ends clamped to said inturned portions and a central clamping device enclosing the front member adjacent its central portion to stiffen and strengthen the same. 110

6. The automobile buffer formed of resilient strip and having a rear transverse member, and having a buffer front member spaced considerably ahead of the lateral portions of said rear member, said rear member having looped end portions extending 120 out into protective position adjacent the automobile wheels and a front reenforcing member secured to the other buffer elements by enclosing clamping devices. 125

7. The automobile buffer formed of resilient strip and having a rear transverse member adapted to be connected to the auto- 130

mobile, and having a buffer front member spaced considerably ahead of the lateral portions of said rear member in line with the automobile frame members, and having 5 looped ends extending out into protective position adjacent the automobile wheels and having a front reenforcing member clamped to the other buffer element by clamping means including a substantially central 10 enclosing clamping device.

8. The automobile buffer formed of resilient strip and having a rear transverse member adapted to be connected to the automobile, and having a buffer front member 15 and having ends extending out into protective position adjacent the automobile wheels and having a front reenforcing member clamped to the other buffer elements by clamping means including a substantially 20 enclosing clamping device.

9. The automobile buffer formed of resilient steel strip and having a rear transverse member, and having a buffer front member spaced considerably ahead of the 25 portions of said rear members substantially in line with the automobile frame members, said rear member having integral looped ends extending out into protective position adjacent the automobile wheels and provided 30 with inturned connector portions extending inward adjacent each other at the central portion of the buffer front and a front reenforcing member clamped to said inturned ends.

35 10. The automobile buffer formed of resilient steel strip and having a rear transverse member, and having a buffer front member spaced considerably ahead of the portions of said rear member substantially 40 in line with the automobile frame members, said rear member having ends extending out into protective position adjacent the automobile wheels and provided with inturned connector portions extending inward adjacent 45 each other at the central portion of the buffer front and a front reenforcing member clamped to the other buffer element.

11. The automobile buffer formed of resilient spring strip and having a rear transverse brace bar portion adapted to be connected to the automobile and having end loops adapted to extend out into protective position adjacent the automobile wheels and having front reenforcing members detachably 50 connected to the other buffer members by enclosing clamping devices comprising lateral clamping devices and an intermediate central clamping device securing and stiffening the buffer front member.

60 12. The automobile buffer formed of resilient spring strip and having a rear transverse portion adapted to be connected to the automobile and having end loops adapted to extend adjacent the automobile wheels and having front reenforcing members con-

nected to the other buffer members by clamping devices comprising lateral clamping devices and an intermediate central clamping device securing and stiffening the buffer front member.

70

13. The automobile buffer formed of resilient steel strip and having looped ends extending out into protective position adjacent the automobile wheels and having a rear transverse member and a buffer front member spaced considerably ahead of the portions of said rear member substantially in line with the automobile frame members, said rear member being provided with in-turned connector portions extending inward adjacent each other at the central portion of the buffer front and a front reenforcing member clamped to said in-turned ends.

75

14. The automobile buffer formed of resilient steel strip and having looped ends 80 extending out into protective position adjacent the automobile wheels and having a rear transverse member and a buffer front member spaced considerably ahead of the portions of said rear member substantially in line with the automobile frame members, said rear member being provided with in-turned connector portions extending inward toward each other at the central portion of the buffer front and the buffer front 85 member clamped to said in-turned ends.

90

15. The automobile buffer formed of resilient strip and having a rear transverse member, attaching members adapted to be connected to the automobile and having connector portions to be adjustably secured to the connector portions of said rear transverse member, and having a buffer front member provided with corresponding portions spaced considerably ahead of the connector portions of said rear member, said rear member having integral looped end portions extending out into protective position adjacent the automobile wheels and having integral inturned connector portions 100 and a front reenforcing member secured to the other buffer element by clamping devices 105 including a substantially central clamping device.

110

16. The automobile buffer formed of resilient strip and having a rear transverse member having connector portions adapted to be secured to the automobile, and having a buffer front member having its corresponding portions spaced considerably ahead of the connector portions of said rear member, said rear member having looped end portions extending out into protective position adjacent the automobile wheels and a front re-enforcing member secured to another of the 115 buffer elements by clamping devices.

120

17. The automobile buffer front formed of resilient strip and having ends adapted to extend out into protective position adjacent the automobile wheels and comprising a rear 125

130

- transverse member provided with connector portions, and comprising a buffer front member provided with corresponding portions spaced considerably ahead of the connector portions of said rear member and a front reenforcing member connected to another of the elements of the buffer by clamping devices including a substantially central clamping device, and buffer attaching members adapted to be connected to the automobile and adjustably secured to the connector portions of said rear transverse member.
18. The automobile buffer front formed of resilient strip and having end loops adapted to extend out into protective position adjacent the automobile wheels and comprising a rear transverse member provided with connector portions adapted to be adjustably connected to the automobile and comprising a buffer front member provided with corresponding portions spaced considerably ahead of the connector portions of said rear member and clamping devices including a substantially central clamping device cooperating with said buffer front member, and buffer attaching members adapted to be connected to the automobile and adjustably secured to the connector portions of said rear transverse member.
19. The automobile buffer front formed of steel strip and having end loops adapted to extend out into protective position adjacent the automobile wheels and comprising a rear transverse member provided with connector portions adapted to be adjustably connected to the automobile and comprising a buffer front member provided with corresponding portions spaced considerably ahead of the connector portions of said rear member and clamping devices including a substantially central clamping device cooperating with said buffer front member.
20. The automobile buffer front having end loops adapted to extend out into protective position adjacent the automobile wheels, and comprising a unitary spring strip rear member having looped end portions and in-turned connector portions and having a transverse supporting portion provided with connector portions adapted to be adjustably connected to the automobile, and comprising a resilient buffer front member spaced at least twice as far ahead of the connector portions of said rear member as the diameter of said end loops and clamping devices securing said buffer front member to said in-turned connector portions.
21. The automobile buffer front having end loops adapted to extend out into protective position adjacent the automobile wheels, and comprising a unitary steel strip rear member having looped end portions and in-turned connector portions and having a transverse supporting portion adapted to be connected to the automobile, and comprising a resilient buffer front member spaced considerably ahead of said rear member as the diameter of said end loops and clamping devices securing said buffer front member to said in-turned connector portions.
22. The resilient automobile buffer front comprising a unitary spring strip rear member having looped end portions and in-turned connector portions and having a substantially straight rear transverse supporting portion adapted to be adjustably connected to the automobile, and comprising a resilient buffer front member spaced considerably ahead of said rear member and clamping devices securing said buffer front member to said in-turned connector portions.
23. The resilient automobile buffer front comprising a unitary spring strip rear member having looped end portions and in-turned connector portions and having a rear transverse supporting portion adapted to be connected to the automobile, and comprising a resilient buffer front member spaced considerably ahead of said rear member and means securing said buffer front member to said in-turned connector portions.
24. The automobile buffer front comprising a unitary rear member having looped end portions and in-turned connector portions and having a rear transverse supporting portion adapted to be connected to the automobile, and comprising a buffer front member spaced considerably ahead of said rear member and means securing said buffer front member to said in-turned connector portions.
25. The automobile buffer formed of resilient strip and having a rear transverse member, and having attaching members adapted to be connected to the automobile and provided with connector portions to be secured to the connector portions of said rear transverse member, and having a buffer front member spaced considerably ahead of the connector portions of said rear member, said rear member comprising a unitary spring steel strip having looped end portions extending out into protective position adjacent the automobile wheels and having integral in-turned connector portions secured to said front member.
26. The automobile buffer formed of resilient strip and having a rear transverse member adapted to be connected to the automobile, and having a buffer front member spaced considerably ahead of said rear member, said rear member comprising a unitary steel strip having end portions extending out into protective position adjacent the automobile wheels and having in-turned connector portions secured to said front member.

GEORGE ALBERT LYON.
